[57] CLAIM

The ornamental design for an area light, as shown and described.

DESCRIPTION

FIG. 1 is a rear perspective view of an area light showing our new design;

FIG. 2 is a top plan view thereof on an enlarged scale;

FIG. 3 is a front elevational view thereof on an enlarged scale;

FIG. 4 is a side elevational view thereof on an enlarged scale, the opposite side being a mirror image.

*Fig. 3.**Fig. 4.*
